(No Model.)

B. F. PATCH.
BURNISHING MACHINE.

No. 377,574.

Patented Feb. 7, 1888.

Benjamin F. Patch.

by Alban Andrew, his att,

UNITED STATES PATENT OFFICE.

BENJAMIN F. PATCH, OF DANVERS, MASSACHUSETTS, ASSIGNOR TO
WILLIAM M. CURRIER, OF SAME PLACE.

BURNISHING-MACHINE.

SPECIFICATION forming part of Letters Patent No. 377,574, dated February 7, 1888.

Application filed July 28, 1887. Serial No. 245,575. (No model.)

To all whom it may concern:

Be it known that I, BENJAMIN F. PATCH, a citizen of the United States, and a resident of Danvers, in the county of Essex and State of Massachusetts, have invented new and useful Improvements in Burnishing - Machines, of which the following, taken in connection with the accompanying drawings, is a specification.

This invention relates to burnishing - machines for burnishing shanks of boots or shoes, and is an improvement on the patent granted to me April 26, 1887, No. 362,036.

My present invention consists of an improved friction heating device for heating the rotary burnishing-tool, and means for regulating the friction, and it is carried out as follows, reference being had to the accompanying drawings, wherein—

Figure 1 represents a side elevation of the improved burnishing - machine, the friction heating device of which is shown in section. Fig. 2 represents a cross-section on the line A B, shown in Fig. 1.

Similar letters refer to similar parts whenever they occur on the different parts of the drawings.

In the drawings, *a* represents a suitable post or standard, to which is secured or made in one piece the frame *b*, having bearings *b'* and *b''* in its upper end for the rotary driving-shaft *c*, provided with fast and loose pulleys *c'* and *c''*, as shown.

To the forward end of the shaft *c* is secured the bevel-gear *c'*, meshing into the teeth of the bevel-gear *d*, secured to the burnisher-shaft *d'*, that is journaled in the bearing *b''* in the frame *b*, as shown. To the lower end of the burnisher-shaft *d'* is secured the metal burnishing-disk *D*, having a concavity, *D'*, on its under side and a thin or rounded annular burnishing-edge, *D''*, as shown.

The features above described are substantially like what are shown and described in my aforesaid Letters Patent, and form no part of my present invention, which consists in an improved friction heating device, and it is carried out as follows:

e is a bracket secured to frame *b* by means of screws *e'* *e''*, or similar devices, or cast or

made in one piece with the frame *b*, as may be 50 most convenient.

At *e''* on the bracket *e* is pivoted the forked friction device *f*, that embraces a portion of the edge of the inverted burnishing-disk *D*, and has attached to the inside of its forked 55 portion the friction-blocks *f'* *f''*, preferably made of leather or analogous material, such blocks being held in contact with the upper or lower portions of the burnishing-disk *D*, or both, as may be desired, with a proper pressure to obtain the desired heat of the said burnishing-tool. The forked piece *f* is provided with ears or extensions *f''* *f''*, as shown in Fig. 1, upon which act the adjustable pressure-rods *g* *g*, said rods being loosely supported 60 in bearings in the frame *b*, and provided with coiled or equivalent springs *g'* *g'* for forcing either or both of said rods against the rear of the ears *f''* *f''* on the pivoted friction heating-block *f*, as may be desired. The rear ends of 70 the springs *g'* *g'* rest against the bottom of the recesses *b'* *b''* in the frame *b*, and their forward ends press against pins or shoulders *g''* *g''* on the rods *g* *g*, as shown in Fig. 1. The rear ends of the rods *g* *g* project out through 75 the rear portion of the frame *b*, and such rearwardly-projecting parts of the rods *g* *g* are screw-threaded and provided with thumb-nuts, or other suitable regulating-nuts, *g''* *g''*, by means of which the pressure of the springs 80 *g'* *g'* can be regulated. It will thus be seen that by adjusting the nuts *g''* *g''* the pressure of the springs *g'* *g'* can be regulated so as to cause the friction-blocks *f'* *f''* to bear against the upper or lower portion of the rotary burnishing-disk *D* with any desired pressure, by 85 which the frictional resistance is obtained to heat the burnishing-disk to the desired temperature during its rotation.

What I wish to secure by Letters Patent, 90 and claim, is—

1. In combination with the rotary burnishing-disk *D*, the forked friction-piece *f* and its blocks *f'* *f''*, pivoted to the frame *b* and provided with the adjustable presser rods *g* *g*, 95 as and for the purpose set forth.

2. In a burnishing - machine, the friction-piece *f* and its blocks *f'* *f''*, pivoted to the

frame *b* and provided with ears or extensions *f*" *f*", in combination with the spring-pressed rods *g* *g*, adapted to bear against the pivoted friction-piece and having the pressure-regulating nuts *g* *g*³, as and for the purpose set forth.

In testimony whereof I have signed my name

to this specification, in the presence of two subscribing witnesses, on this 25th day of May, A. D. 1887.

BENJAMIN F. PATCH.
